UNITED STATES PATENT OFFICE.

THOMAS BOYLAN, OF ELK MOUNTAIN, WYOMING.

RAILWAY-RAIL.

SPECIFICATION forming part of Letters Patent No. 751,372, dated February 2, 1904.

Application filed September 12, 1903. Serial No. 172,955. (No model.)

To all whom it may concern:

Be it known that I, THOMAS BOYLAN, a citizen of the United States, residing at Elk Mountain, in the county of Carbon and State of Wyoming, have invented new and useful Improvements in Railway-Rails, of which the following is a specification.

This invention relates to railway-rails, and particularly to a rail joint or splice; and the primary object of the invention is to provide a joint of new and improved construction and simple and effective arrangement of parts whereby the use of fish-plates, chairs, and other similar attachments may be avoided and pounding of the car-wheels on the contiguous rail ends, as well as sinking of the latter at the joints, is prevented.

A further object of the invention is to provide a rail joint or splice having interlocking parts which are assembled or disassociated by a lateral movement of the rail ends, requiring but a single fastening inserted through the base-flanges of the rails to effect a reliable interlock of the coöperating parts of such nature as to resist accidental separation and loose movement.

With these and other objects and advantages in view the invention consists in the construction and arrangement of the several parts, which will be more fully hereinafter described and claimed.

In the drawings, Figure 1 is a perspective view of portions of rails connected by a joint or splice embodying the features of the invention. Fig. 2 is a detail perspective view of the extremity of one rail. Fig. 3 is a detail perspective view of the extremity of the interlocking rail.

Similar numerals of reference are employed to indicate corresponding parts in the several views.

The numerals 1 and 2, respectively, designate two rails, the terminal of the rail 1 having the base-flange 3 cut away transversely in a horizontal plane, as at 4, to provide a seat which includes a transverse slot 5, the flange having a vertical opening 6 therethrough near the outer end of the said slot. The seat 4 and slot 5 terminate at an inner guard-rib 7, 45 extending longitudinally of the rail in line

with the further side of the web, as illustrated by Fig. 2. The terminal of the rail 1 where the seat 4 and slot 5 are formed has the web cut away, as at 9, and the under portion of the head 10 of the rail is shouldered, 55 as at 11, and constructed with a transverse slot 12. By shouldering the under portion of the head of the rail the free extremity of the latter above the seat 4 and slot 5 is reduced, and at the same time an interlocking member 13 is 60 produced.

The terminal of the rail 2 has the base-flange 14 thereof cut away at one side close to the web 15, the flange being removed a distance equal to the depth of the undercut portion of the rail-terminal 1. The opposite part of the flange 14 of the rail-terminal 2 is constructed with a vertical opening 16, which is adapted to coincide with the openings 6 in the terminal of the rail 1, and at a suitable 65 distance inwardly from the end of the rail 2 a slot 17 is cut transversely through the lower portion of the flange 14 and terminates at the opposite side coincidently with the vertical wall 18 of the reduced portion of the flange 14. 70

The formation of the slot 17 provides a locking member 19 adjacent to the end of the rail 2 to fit in the slot 5, and the seat 4 enters the said slot 17 when the two rail-terminals are associated. The end of the head 20 of the rail 2 is cut away to form an interlocking terminal 21 to fit in the slot 12 of the overhanging portion of the head 10 of the rail 1. The head 20, adjacent to the terminal 21, is also transversely slotted, as at 22, to a sufficient depth 75 to form a receptive means for the locking member 13 of the head 10 of the rail 1, the proportions of the interlocking terminals of the two rails being such as to permit the ends of the webs to closely contact, as shown by 80 Fig. 1.

From the foregoing it will be seen that the terminal of the rail 2 is moved laterally into the opening formed in the terminal of the rail 1 by removing the web and that the said terminal of the rail 2 when moved laterally into the end of terminal of the rail 1 will be limited in such movement by the straight wall 18 of the cut-away portion of the flange 14 contacting with the guard-ribs 7. When this 95 100

contact between the said wall 18 and guard-rib is effected, the remaining portions of the rail-terminals will be in close interlocked relation and the opening 16 will aline with the opening 6. To complete the securement of the joint, a fastening-spike is driven through the alining openings 6 and 16 into a tie or support for the rails, and when this operation has been completed it will be seen that it will be impossible for the rail-terminals to work loose or become disassociated, and further vertical movement will be obstructed, with advantages in rail structure. Longitudinal movement of the rail ends will be prevented in view of the interlocking projections in the contiguous parts, and thus the use of a fish-plate or other similar fastening means is avoided.

Rails equipped with the improved joint or splice can be readily assembled, and if at any time it becomes necessary to separate the rails the removal of the single fastening device engaging the openings 6 and 16 will permit such operation to be readily pursued.

Changes in the proportions and dimensions may be resorted to without departing from the spirit of the invention.

Having thus fully described the invention, what is claimed as new is—

1. A rail-joint, comprising rail-terminals, one of which has the web removed to permit the head to overhang the base-flange, said head being shouldered and formed with a transverse slot and the base provided with a seat and a

slot extending transversely over a portion 35 thereof and terminating at a longitudinal rib, and the other rail end having its base-flange cut away at one side and formed with upper and lower slots, and reduced portions to enter the opening in the end of the other rail and 40 interlock with the latter.

2. A rail-joint, consisting of rail ends, one of which has an opening extending therethrough between the head and flange, and a longitudinal rib extending upwardly from the 45 base, the other rail end having the flange cut away at one side and formed with an under transverse slot and the head reduced and transversely slotted and adapted to be inserted laterally into the end of the first-mentioned rail, 50 and a single fastening passing through portions of both rail ends.

3. A rail-joint, consisting of rail ends, one of which has an opening cut therethrough between the base-flange and head and also provided with a longitudinal rib rising from the base-flange at one side of the center, the other rail end having upper and lower transverse slots and a portion of one side of the base-flange thereof removed and adapted to contact 60 with the rib, and means for fastening the interlocked rail ends.

In testimony whereof I affix my signature in presence of two witnesses.

THOMAS BOYLAN.
